United States Patent Office.

HORACE J. WICKHAM, OF MANCHESTER, CONNECTICUT, ASSIGNOR TO
JOSEPH RECKENDORFER, OF NEW YORK CITY.

Design No. 4,566, dated January 10, 1871.

DESIGN FOR A COMBINED PENCIL AND RECEPTACLE.

The Schedule referred to in these Letters Patent and making part of the same.

To whom it may concern:

Be it known that I, HORACE J. WICKHAM, of Manchester, in the county of Hartford and State of Connecticut, have invented a new and original Design for Combined Pencil and Receptacle for Erasers and other articles, of which the following is a specification.

The nature of my design is illustrated in the accompanying drawing, in which—

Figure 1 is an elevation of the pencil and receptacle head.

Figure 2 is a longitudinal central section of the same, representing the receptacle filled with a rubber eraser.

Figure 3 is a like section, representing the receptacle-head empty.

The lead-pencil A is of ordinary construction and shape. Upon its end is mounted a cylindrical case,

B, upon the exterior of which a bead, a, may be formed, as shown.

Over the open end of the case fits a removable cap or cover, B, of cylindrical shape.

The case is adapted to hold the rubber eraser b, or other article, and the cap B covers the article so as to protect the latter from being soiled or injured when not in use.

What I claim as my invention is—

The design for a combined pencil and receptacle-head, as shown.

In witness whereof I have hereunto set my hand in the presence of two subscribing witnesses.

HORACE J. WICKHAM.
